UNITED STATES PATENT OFFICE

162,840

COMBINATION LICENSE PLATE HOLDER AND SIGNAL LIGHT HOUSING

Kaufman T. Keller, Detroit, Mich., assignor to
Chrysler Corporation, Highland Park, Mich., a
corporation of Delaware

Application August 13, 1949, Serial No. 4,485

Term of patent 7 years

(Cl. D14—6)

To all whom it may concern:

Be it known that I, Kaufman T. Keller, a citizen of the United States, residing in the city of Detroit, county of Wayne, and State of Michigan, have invented a new, original, and ornamental Design for a Combination License Plate Holder and Signal Light Housing, of which the following is a specification, reference being had to the accompanying drawings, forming part thereof, in which:

Fig. 1 is a perspective view of my combination license plate holder and signal light housing;

Fig. 2 is a front elevation of the combination license plate holder and signal light housing;

Fig. 3 is a top plan view of the combination license plate holder and signal light housing;

Fig. 4 is a bottom view of the combination license plate holder and signal light housing;

Fig. 5 is an end elevation viewed from the left end of Fig. 2; and

Figs. 6, 7 and 8 are sectional views taken on the lines 6—6, 7—7 and 8—8 of Fig. 2.

The dotted line showing in Fig. 2 is for illustrative purposes only.

I claim:

The ornamental design for a combination license plate holder and signal light housing, substantially as shown and described.

KAUFMAN T. KELLER.
